REEL

Hilyard C. Howsam, Chicago, Ill., assignor to
 Hubbard Spool Company, Chicago, Ill., a corpora-
 tion of Illinois

Application August 19, 1933, Serial No. 685,839

11 Claims. (Cl. 242—124)

My invention relates to reels for comparatively heavy service, such as holding wire. Reels for this type of service are subjected to heavy duty as the heavily loaded reels are frequently dropped 5 to a considerable distance from a truck or from a stack.

The invention concerns particularly that type of structure in which reel heads are detachably secured to the ends of a metallic drum structure 10 usually of sheet metal, with the heads constructed solely of sheet metal or of sheet metal with filler and stiffening material, such as wood. Bolts extending through the heads and the drum are usually employed for securing the heads rigidly 15 against the drum ends. Where these heads have only the comparatively thin edges at the drum ends for seating supports, drawing up of the bolts extending through the drum will put the heads to unnecessary strain and will tend to warp or dish 20 them and furthermore there will not be sufficient and rigid securing of the heads to prevent twisting or racking of the reel structure and loosening or distortion of the parts under the heavy duty and treatment to which the reels are apt to be subjected. 25

The important object of the invention is, therefore, to provide structure on the drum which will not only materially strengthen the drum itself but will afford sufficiently extensive seating surface 30 for the heads around the bolts so that the heads may be securely and unyieldingly clamped to the drum ends without being strained and distorted and the entire structure will be sufficiently strengthened against twisting and racking and 35 loosening or distortion of the various parts so that the reel structure may endure and retain its shape and rigidity under the severe duty to which it is subjected in service.

The invention contemplates the provision of 40 substantially semi-tubular truss or brace members extending in axial direction in the drum and rigidly secured to the drum against the inner side thereof, these braces or trusses receiving the bolts and being provided at their outer ends with 45 radially extending flanges which, together with the ends of the drum shell, afford adequate seating surface around the bolts for the heads.

Means are further provided for rapid accurate 50 alignment both axially and circumferentially of the supporting or brace members for securing thereof to the drum shell, preferably by means of spot-welding.

The various features of the invention are 55 incorporated in the structure disclosed on the accompanying drawing, in which drawing—

Figure 1 is an end view of the reel with one head partly broken away;

Figure 2 is a section on plane II—II of Figure 60 1; and

Figure 3 is an enlarged section on plane III—III of Figure 2.

Referring to the drawing, the drum structure comprises a cylindrical shell 10 cut from a piece of rectangular sheet metal with its ends abutting and held together by a plate 11 engaging along the inner sides of the ends and secured thereto preferably by spot-welding. A number of truss or strengthening and supporting members A are supported on the inside of the drum, three such members being shown. The members are formed integral of sheet metal each comprising a body 12 of substantially semi-circular cross sections from whose ends ears 13 are deflected for fitting and seating against the inner sides of the drum shell 10, the securing being preferably by means of spot-welding. These semi-tubular members together with the sections of the drum shell 10 spanned thereby form channels for receiving the bolts B which secure the head structures H to the drum. The outer ends of the members 12 are deflected radially inwardly to form seating flanges 14 which flanges together with the ends of the shell 10 provide the seating surfaces around the bolts for the head structure. To lighten the 75 structure and eliminate unnecessary weight, the body 12 of the members A may be cut away between the ears 13 as indicated at 15. 80

Each head structure, as shown, comprises an annular metallic disc 16 having its peripheral 90 portion deflected outwardly to form a cylindrical flange 17 which is circumferentially indented as indicated at 18 to form a runway for belts for rotating the reel structure for winding thereof. Surrounding the central opening 19 of the disc 95 16 is the inwardly extending flange 20 deflected from the disc, this flange snugly fitting into the end of the drum shell 10, and to receive this flange sufficient clearance space is provided between the ends of the members A and the shell 100 10 and the ears 13 are set inwardly.

The disc 16 and peripheral flange 18 of each head structure receives a filler 21 preferably built up of layers or plies of wood with the grain of the layers crossing. The outer peripheral portion 18' of the flange 18 is deflected around against the outer face of the filler so that the peripheral portion of the filler is securely clamped. The filler has a central opening 22 concentric with the drum 10 and a tubular sheet metal rivet 23 is extended through the opening and deflected at its ends against the respective faces of the filler to securely clamp said filler and to reinforce said filler at this point, the rivets or thimbles also serving as bearing bushings when 110 the reel is supported on a shaft extended through these bushings for winding or unwinding thereof. The head structures thus formed of wood and reinforcing sheet metal are very strong and rigid structures. 115

The heads have bolt holes 24 spaced to align with the passageways through the members A to receive the bolts B. Cup washers 25 are provided for the bolt heads and the bolt nuts 26 these washers being sunk into pockets or recesses 27 formed in the wood filler of the head and have the seating flanges 28. The bolts are of a length so that after assembly the ends thereof will not extend beyond the outer faces of the heads and 10 in order that the nuts may be more readily applied they are provided with threaded necks 26'.

To assemble the structure, the heads are applied to the ends of the drum shell with the bolt holes 24 in alignment with the passageways 15 through the members A and then the bolts are slipped through and the nuts 26 applied. The members A at their flanged ends extend axially a short distance beyond the edges of the drum to the extent of the thickness of the discs 16 of 20 the heads so that when the nuts are drawn up the discs 16 will abut the edges of the drum 10 and the wood filler will seat against the flanges of the members A, the flanges 20 of the discs 16 extending into and engaging against the inner 25 face of the drum so as to properly center the heads relatively to the drum. Adequate seating surface is thus provided for the heads all around the bolts so that the pressure resulting against the heads when the bolts are drawn up tight will 30 be distributed around the bolts and the heads will be drawn up tightly and securely into final position without being subjected to strain or to distortion or dishing. The extended area also greatly increases the engagement friction so that 35 relative rotational movement between the heads and drum will be prevented. The members A will materially strengthen and stiffen the drum structure itself against distortion and the reel structure becomes very resistant to twisting or 40 racking or distortion or loosening of the parts thereof and will remain intact and fit for the heavy service for which it is intended.

To facilitate assembly of the drum structure and to insure correct circumferential and axial 45 alignment of the members A, the supporting ears 13 therefor may be provided with deflections or teats 29 and the drum shell 10 provided with holes 30 accurately located. Then when the members A are to be secured, they are applied 50 with the projections 29 extending into the openings 30 for accurate alignment thereof and the structures are then secured, as by spot-welding the ears 13 to the drum shell 10.

I thus produce a strong, durable and economically manufactured reel structure which will stand up under heavy service and from the drum 55 of which the heads may be readily removed for repairs or replacement.

I have shown a practical embodiment of the 60 various features of my invention, but I do not desire to be limited to the exact construction and arrangement shown and described, as changes and modifications may be made without departing 65 from the scope of the invention as defined in the appended claims.

I claim as follows:

1. A reel comprising a pair of heads, a drum 70 between said heads, said heads having bolt holes and bolts extending therethrough and through the drum for securing the heads to the drum against the ends thereof, reinforcing structures for said drum extending through and secured 75 against the inner side thereof and surrounding said bolts, and flanges at the outer ends of said

structures affording additional seating support for said heads.

2. A reel comprising a pair of heads, a drum 80 between said heads, longitudinally extending brackets secured to the inner side of the drum and cooperating with the drum wall to form channels, the outer ends of said brackets being in alignment with the drum ends, and bolts extending through said heads and channels for securing said heads against the outer ends of said drum and said brackets. 85

3. A reel comprising a pair of heads, a sheet metal drum between said heads, longitudinally extending brackets of sheet metal secured against the inner side of said drum to define channels, 90 the outer ends of said brackets having radially inwardly extending flanges forming seats for said heads, and bolts extending through said heads and said channels for securing said heads against the ends of said drum and said bracket 95 flanges.

4. A reel comprising a pair of heads, a cylindrical sheet metal drum between said heads, longitudinally extending semi-tubular brackets of sheet metal secured against the inner side of said 100 drum at spaced intervals, said brackets at their outer ends being deflected radially inwardly to form seating flanges in alignment with the ends of said drum, and bolts extending through said heads and said brackets for securing said heads 105 into seating engagement with the drum ends and with the bracket flanges.

5. A reel comprising a sheet metal drum, semi-tubular sheet metal brackets extending longitudinally in said drum and secured with their 110 edges against the inner side of the drum, the outer ends of said brackets being deflected radially to form seating surfaces in alignment with the drum ends, a pair of heads, and bolts extending through said heads and said brackets for securing said heads against the outer ends of the 115 drum and said bracket flanges.

6. A reel comprising a cylindrical sheet metal drum, semi-tubular sheet metal brackets secured at their edges against the inner side of the drum 120 to cooperate with the drum walls to define bolt-receiving passageways, the outer ends of said brackets being deflected radially inwardly to form seating flanges, heads for said drum, and bolts extending through said heads and said passageways for securely seating and securing the heads against the drum ends and said flanges. 125

7. A reel comprising a cylindrical metal drum, sheet metal brackets secured to the inside of said drum and spanning sections thereof to form 130 therewith bolt-receiving passageways, the outer ends of said brackets aligning with the drum ends to provide additional seating surfaces, heads for said drum, and bolts extending through said heads and said passageways for seating and securing said heads against the ends of said drum and said brackets. 135

8. A reel comprising a sheet metal drum, heads for the ends of said drum, said heads comprising each an annular metal disc having a centering flange at its inner perimeter for fitting and engaging in the respective end of the drum, and a non-metallic filler surrounded and secured by the disc, brackets secured to the inner side of the drum and having seating flanges at their ends 140 for engagement by the filler, and bolts extending through the heads and said brackets for securing the heads to the drum with the discs against the drum ends and the fillers against the bracket flanges. 145

9.	A reel comprising a pair of heads, a drum between said heads, reinforcing structures for said drum extending therethrough and secured to the inner side thereof, the outer ends of said structures being in alignment with the drum ends, and bolts extending through said heads and structures for securing said heads against the outer ends of said drum and said structures.	drum ends and the filler structures against the ends of said reinforcing structures.
10.	A reel comprising a sheet metal drum, heads on the ends of said drum, each head comprising an annular metal disc having a centering flange at its inner perimeter for fitting and engaging in the respective end of the drum, and a filler structure surrounded and secured by the disc, reinforcing structures for the drum extending therethrough and secured to the inner side thereof, and bolts extending through said heads and said reinforcing structures for securing the heads to the drum with the discs against the	11. A reel comprising a sheet metal drum, heads on the ends of said drum, each head comprising an annular sheet metal structure having a centering flange at its inner perimeter for fitting and engaging in the respective end of said drum and a filler structure surrounded and secured by the disc structure, sheet metal reinforcing members for said drum extending therethrough from end to end and secured to the inner side thereof and having seating flanges at their ends, and bolts extending through said heads and said reinforcing members for securing the heads to the drum with said disc structure against the drum ends and said filler structures against said flanges.
